UNITED STATES PATENT OFFICE.

EDMOND A. FORDYCE, OF BOSTON, MASSACHUSETTS, ASSIGNOR TO
LAMSON CONSOLIDATED STORE SERVICE COMPANY, OF NEWARK,
NEW JERSEY, A CORPORATION OF NEW JERSEY.

PNEUMATIC-DESPATCH-TUBE APPARATUS.

No. 813,636.

Specification of Letters Patent.

Patented Feb. 27, 1906.

Application filed March 24, 1905. Serial No. 251,770.

To all whom it may concern:

Be it known that I, EDMOND A. FORDYCE, of Boston, in the county of Suffolk and State of Massachusetts, have invented certain new and useful Improvements in Pneumatic-Despatch-Tube Apparatus, of which the following is a specification.

My invention relates to improvements in pneumatic-despatch-tube apparatus; and its object is to devise an apparatus on the vacuum principle which is economical and efficient and through which air passes only when the apparatus is in use transmitting carriers between stations.

My invention consists of certain novel features hereinafter described, and particularly pointed out in the claims.

In the accompanying drawings, which illustrate a construction embodying my invention, Figure 1 is a side elevation in section of the apparatus in its normal condition with no carriers in transit. Fig. 2 is a side elevation, partly in section, showing the position of the parts upon the insertion of a carrier for despatch at the central station. Fig. 3 is a side elevation, partly in section, showing the position of the parts upon the position of a carrier for transmission at a substation.

Like letters of reference refer to like parts throughout the several views.

The transit-tube A for transmission of the carriers from the central station to a substation has a bell-mouth opening, as shown, to receive the carriers. Said tube leads to the upward discharge-terminal A', having a suitable valve A² closing the despatch-opening and of the usual construction in the art. Connected to said terminal A' is a tube B for returning the carriers to the central station, and at its upper end said tube is provided with a carrier-inlet opening, closed by the valve B⁴ of usual construction, and at the lower end of said tube B is a suitable valve B' for closing same. Connected to the lower end of said tube B by a joint B² is a tube B³, which is in communication with said tube B² by suitable slots, as shown. The tube B³ is connected below the floor-line (indicated by the letter R) to the chamber C, in which is located the valve D, closing the upper end of the passage J, which is in communication, by means of the pipe K, with the suction-tank K'.

This valve D is pivoted at D' in the chamber C and has a rolling contact at D² with the piston-rod D³ of the piston E', working in the cylinder E. To the lower end of the cylinder E is connected the pipe F, which when the apparatus is not in use in transmitting carriers is closed at its outer end to the atmosphere by the lever G, pivoted on the support G² and with its upper end removed from contact with the magnet G', as indicated in Fig. 1, and in this condition of the parts the piston E' is in the lower part of the cylinder E and the valve D is closed. With the parts in the position shown in Fig. 1 the pump is exhausting from the passage J to the pipe K, through the tank K', and through the upper and lower openings L and M, which connect the cylinder E with the passage J and pipe K, and this suction through said openings L and M produces a vacuum on both sides of the piston E', and as the vacuum created in said cylinder by the openings L and M under the suction of the pump is equal on both sides of the piston E' said piston drops by gravity to the lower part of the cylinder E, as shown, which closes the valve D. From the magnet G' extend the wires H H', through which when the circuit is closed through said wires the battery H², as hereinafter explained, will energize the magnet G' and cause the operation hereinafter described.

When a carrier is to be sent from the central station to a substation through the terminal A', it is inserted into the bell-mouth, Fig. 2, and striking the finger P will cause its inner end to cover the contact-points of the wires P' P², which will close the circuit, as just described, and energize the magnet G', drawing the upper end of the lever G inward toward the magnet and opening the end of the pipe F to the atmosphere, and air entering through the pipe F under the piston E' will destroy the vacuum below the piston E' and force it upwardly, as the vacuum is maintained through the opening L. This operation will cause the valve D to open, so that air is drawn from the atmosphere at the bell-mouth through the system to the tank K', and the carrier will be drawn through the tube A and discharged through the valve A² at the terminal A'. After a carrier has passed the finger P said finger will move from the po-

sition shown in Fig. 2 to that shown in Fig. 1, as the outer end is weighted to normally prevent the closing of the circuit, and as the circuit is broken the magnet becomes deenergized and the lower end of the lever G will close the pipe F to the atmosphere, and as the suction continues through the passages L and M the vacuum will become equal and the piston E' will gradually lower, thereby closing the valve D when the vacuum through the system is cut off and exists only below the valve D. When a carrier is to be sent from a substation to the central station, it is inserted into the tube B by opening the valve B' and moving downwardly will strike the outer end of the finger Q, which will raise the inner end of said finger and close the circuit through the wires H H', and the operation is the same as above described for raising the valve D to allow suction through the system to transmit a carrier which opens the valve B' and drops said carrier into a suitable receptacle, as indicated at R'. After the carrier has passed the finger Q, its inner end being weighted, it will move from engagement with the contacts and assume the position shown in Fig. 2.

The passage through the opening M to the bottom of the cylinder E' is controlled by the valve N, which may be adjusted and held in its adjusted position by the nuts N'. For long lines the valve N is so adjusted that the fall of the piston E' would be slow, allowing for the discharge of the carrier before the valve D is closed and the vacuum cut off, while in short lines the valve N would be wide open, so that the piston E' would drop quickly because the carrier has a short distance to travel.

Having thus described the nature of my invention and set forth a construction embodying the same, what I claim as new, and desire to secure by Letters Patent of the United States, is—

1. In an apparatus of the character described, a transit-tube through which carriers are transmitted, an air-valve controlling the passage of air through said tube and normally closed, an exhaust-tube, mechanism under the control of said exhaust-tube for operating said valve, an electric circuit for controlling said mechanism, and mechanism operated by the insertion of a carrier into said tube to close said circuit for opening said air-valve and allowing a passage of air through said tube for driving carriers.

2. In an apparatus of the character described, a transit-tube through which carriers are transmitted, an air-valve controlling the passage of air through said tube and normally closed, an exhaust-tube, mechanism under the control of said exhaust-tube which normally holds said air-valve closed, an electric circuit for controlling said mechanism, and mechanism operated by the insertion of

a carrier into said tube to close said circuit for opening said air-valve to allow a passage of air through said transit-tube.

3. In an apparatus of the character described, a transit-tube through which carriers are transmitted, an air-valve controlling the passage of air through said tube and normally closed, an exhaust-tube, mechanism under the control of said exhaust-tube for operating said valve, an electric circuit for controlling said mechanism, and mechanism operated by the carrier upon its insertion into the transit-tube to close said circuit for opening said air-valve, and allowing the closing of said air-valve after the insertion of the carrier.

4. In an apparatus of the character described, a transit-tube through which carriers are transmitted, an air-valve for controlling the passage of air through said transit-tube and normally closed, an exhaust-tube, mechanism under the control of said exhaust-tube which normally holds said air-valve closed, an electric circuit for controlling said mechanism, and means operated by the closing of said circuit for admitting atmospheric pressure to said mechanism to open said air-valve upon the insertion of a carrier into said transit-tube to allow a passage of air through said transit-tube for the transmission of carriers.

5. In an apparatus of the character described, a transit-tube through which carriers are transmitted, an air-valve for controlling the passage of air through said transit-tube and normally closed, an exhaust-tube, mechanism under the control of said exhaust-tube which normally holds said air-valve closed, an electric circuit for controlling said mechanism, means operated by the closing of said circuit for admitting atmospheric pressure to said mechanism to open said air-valve upon the insertion of a carrier into said transit-tube to allow a passage of air through said transit-tube for the transmission of carriers, and means for regulating the closing of said air-valve.

6. In an apparatus of the character described, a transit-tube through which carriers are transmitted, an air-valve controlling the passage of air through said tube and normally closed, an exhaust-tube, mechanism under the control of said exhaust-tube for operating said valve, an electric circuit for controlling said mechanism, and mechanism operated by the carrier upon its insertion into the transit-tube to close said circuit for opening said air-valve, allowing the closing of said air-valve after the insertion of the carrier, and means for regulating the closing of said air-valve.

7. In an apparatus of the character described, transit-tubes through which carriers are transmitted in opposite directions, an air-valve controlling the passage of air

through said transit-tubes and normally closed, an exhaust-tube in communication with both of said transit-tubes, mechanism under the control of said exhaust-tube which 5 normally holds said air-valve closed, an electric circuit for controlling said mechanism, and means operated by the closing of said circuit for admitting atmospheric pressure to said mechanism to open said air-valve 10 upon the insertion of a carrier into said transit-tube to allow a passage of air through said transit-tubes for the transmission of carriers.

8. In an apparatus of the character described, transit-tubes through which carriers are transmitted in opposite directions, 15 an air-valve controlling the passage of air through said transit-tubes and normally closed, an exhaust-tube in communication with both of said transit-tubes, mechanism 20 under the control of said exhaust-tube which normally holds said air-valve closed, an electric circuit for controlling said mechanism, and means operated by a carrier inserted into either of said transit-tubes to close 25 said circuit for admitting atmospheric pressure to said mechanism to open said air-valve to allow a passage of air through said transit-tubes for the transmission of carriers.

9. In an apparatus of the character described, a transit-tube through which carriers are transmitted, an air-valve controlling the passage of air through said tube and normally closed, an exhaust-tube, an electric circuit, and mechanism under the control of 35 said exhaust-tube for opening said valve upon the closing of said circuit and allowing the passage of air through said transit-tube for the transmission of carriers.

10. In an apparatus of the character described, a transit-tube through which carriers are transmitted, an air-valve controlling the passage of air through said tube and normally closed, an exhaust-tube, an electric circuit, and mechanism under the control of 45 said exhaust-tube for automatically opening said valve upon the closing of said circuit and allowing the passage of air through said transit-tube for the transmission of carriers.

11. In an apparatus of the character described, a transit-tube through which carriers are transmitted, an air-valve controlling the passage of air through said tube and normally closed, an exhaust-tube, an electric circuit, and mechanism under the control of 55 said exhaust-tube for automatically opening said valve upon the closing of said circuit and allowing the passage of air through said transit-tube for the transmission of carriers, and for automatically allowing said air-valve to 60 move into its closed position after the insertion of the carrier.

12. In an apparatus of the character described, a transit-tube through which car-

riers are transmitted, an air-valve controlling the passage of air through said tube, an exhaust-tube in communication with said transit-tube and normally closed by said air-valve, mechanism under the control of said exhaust-tube and normally holding said air-valve closed, an electric circuit, and means 70 for admitting atmospheric pressure to said mechanism upon the closing of said circuit to open said air-valve to allow the passage of air through said transit-tube for the transmission of carriers. 75

13. In an apparatus of the character described, a transit-tube through which carriers are transmitted, an air-valve controlling the passage of air through said tube, an exhaust-tube in communication with said transit-tube and normally closed by said air-valve, mechanism under the control of said exhaust-tube and normally holding said air-valve closed, an electric circuit, and means 80 operated upon the closing of said circuit for admitting atmospheric pressure to said mechanism to open said air-valve to allow the passage of air through said transit-tube for the transmission of carriers and adapted to cut off atmospheric pressure from said mechanism to allow said mechanism to close said air-valve. 85 9c

14. In an apparatus of the character described, a transit-tube through which carriers are transmitted, an air-valve controlling the passage of air through said tube, an exhaust-tube in communication with said transit-tube and normally closed by said air-valve, mechanism under the control of said exhaust-tube and normally holding said air-valve closed, an electric circuit, and means 95 operated upon the closing of said circuit for admitting atmospheric pressure to said mechanism to open said air-valve to allow the passage of air through said transit-tube for the 100 transmission of carriers and adapted to cut off atmospheric pressure from said mechanism to close said air-valve automatically. 105

15. In a pneumatic-tube system, the combination of a pneumatic tube, two or more stations thereon, a vacuum-pipe connected to said tube, an air-valve controlling said connection and normally closed, an electrically-controlled mechanism for opening said valve, a circuit-wire for said mechanism, and means at each station for opening and closing said circuit and energizing or deenergizing the valve-actuating magnet. 110 115

In testimony whereof I have signed my name to this specification, in the presence of two subscribing witnesses, this 16th day of March, A. D. 1905.
